US00D657844S

(12) United States Design Patent
Smiedt et al.

(10) Patent No.: US D657,844 S
(45) Date of Patent: * Apr. 17, 2012

(54) WATER TREATMENT HOUSING

(75) Inventors: Richard Smiedt, New York, NY (US);
Karim Rashid, New York, NY (US)

(73) Assignee: Move Collective LLC, New York, NY
(US)

() Term: 14 Years

(21) Appl. No.: 29/393,505

(22) Filed: Jun. 6, 2011

Related U.S. Application Data

(62) Division of application No. 29/386,764, filed on Mar. 4, 2011.

(51) LOC (9) Cl. 23-01

(52) U.S. Cl. D23/209

(58) Field of Classification Search D23/207, D23/209, 210; 210/266, 473, 477, 282, 232

See application file for complete search history.

(57) CLAIM

The ornamental design for the water treatment housing, as shown and described.

DESCRIPTION

FIG. 1 is an isometric view of a water treatment housing according to the present design.

FIG. 2 is a plan view of the present design.

FIG. 3 is a bottom view of the present design.

FIG. 4 is a front view of the present design; and,

FIG. 5 is a front view of the present design when used in conjunction with an illustrative pitcher.

The broken line showings are for illustrative purposes only and form no part of the claimed design.
